CHILD'S CONVERSION SEAT FOR A DENTAL CHAIR

Kenneth C. Kerr, 1222 S. Riverside, Medford, Oreg.

Filed Mar. 14, 1960, Ser. No. 59,724

Term of patent 14 years

(Cl. D15—3)

FIGURE 1 is a perspective view of a child's conversion seat for a dental chair showing my new design;

FIGURE 2 is a front elevational view with portions thereof broken away for convenience of illustration;

FIGURE 3 is a side elevational view with a portion thereof broken away for convenience of illustration;

FIGURE 4 is a top plan view.

The back of the seat is plain and unornamented.

I claim:

The ornamental design for a child's conversion seat for a dental chair, as shown and described.
